US00D553361S

(12) **United States Design Patent** (10) **Patent No.:** **US D553,361 S**
(45) **Date of Patent:** **** Oct. 23, 2007**

(54) **HANDBASKET**

(75) Inventors: **William D. Splain**, Brooklyn Park, MN (US); **Robert D. Peota**, Minneapolis, MN (US); **Alexandre Hennen**, Cambridge, MA (US); **Allan Cameron**, Natick, MA (US)

(73) Assignee: **Target Brands, Inc.**, Minneapolis, MN (US)

(**) Term: **14 Years**

(21) Appl. No.: **29/262,603**

(22) Filed: **Jul. 6, 2006**

(51) **LOC (8) Cl.** **03-01**

(52) **U.S. Cl.** **D3/304**

(58) **Field of Classification Search** ..... D3/304-305, D3/307, 309, 311-312, 314-315; D6/510, D6/525; D7/602, 608, 709; D9/429-430, D9/425, 771, 738-739; D22/136; D32/3, D32/37, 53; 232/1 B; 217/126, 18; 220/659, 220/669

CLAIM

The ornamental design for a handbasket, as shown and described.

DESCRIPTION

FIG. 1 is an isometric view of a handbasket according to an embodiment of the invention, with elements in dashed lines forming no part of the claimed design and FIG. 1 showing a handle in a raised, in-use position.

FIG. 2 is a front view of a handbasket, according to an embodiment of the invention, with a rear view being a mirror image of the front view and with elements in dashed lines forming no part of the claimed design.

FIG. 3 is a left side view of a handbasket, according to an embodiment of the invention, with a right side view being a mirror image of the left side view.

FIG. 4 is a top view a handbasket, according to an embodiment of the invention.

FIG. 5 is a bottom view of a handbasket, according to an embodiment of the invention; and,

FIG. 6 is a top view of a handbasket, according to an embodiment of the invention, with FIG. 6 illustrating the same embodiment of FIGS. 1 and 4 except showing the handle in a lowered, storage position, it being understood that all other surfaces are the same as the embodiment of FIGS. 1 and 4.
